UNITED STATES PATENT OFFICE.

LOUIS ESCHNER, OF PHILADELPHIA, PENNSYLVANIA.

CLOSURE FOR BOTTLES AND JARS.

No. 914,258.

Specification of Letters Patent.

Patented March 2, 1902.

Application filed November 23, 1901. Serial No. 404,411.

To all whom it may concern:

Be it known that I, LOUIS ESCHNER, a citizen of the United States, residing in Philadelphia, Pennsylvania, have invented certain Improvements in Closures for Bottles and Jars, of which the following is a specification.

The object of my invention is to provide a closure for a bottle, jar, can, or other receptacle, (hereinafter, for convenience, termed a "jar") which can be readily applied or removed, but which, when applied, will be securely locked in position against accidental displacement and will impart such pressure to the cover of the jar as to insure the desired sealing of the same, the pressure being, by preference, a yielding one which will permit the cover to raise when subjected to a lifting influence in excess of that which it is normally designed to resist. This object I attain in the manner hereinafter set forth, reference being had to the accompanying drawing, in which—

Figure 1 is a vertical sectional view of the mouth portion of a jar with closure therefor constructed in accordance with my invention; Fig. 2 is a perspective view of the mouth portion of the jar; Fig. 3 is a perspective view, showing, in an inverted position, a cap employed in connection with the cover of the jar to effect closure of the same, and Figs. 4 and 5 are vertical sectional views, Fig. 6 is a plan or top view; Fig. 7 is a vertical sectional view, and Fig. 8 is a perspective view illustrating other embodiments of my invention.

Referring in the first instance to Figs. 1, 2, and 3 of the drawing, 1 represents the upper portion of a jar having a flat top surrounding the mouth, and having seated upon it a cover 2 whereby the closing of the jar is effected, this cover being made of metal, paper, or other available material, and being, if desired, coated with paraffin or the like, in order to aid in forming a hermetically sealed joint between the cover and its seat. Around the upper end of the jar is an interrupted rib, the interruptions being preferably formed by making some portions 3^a of the rib, thinner than the other portions 3 of the same, and, in the under side of each of the thicker portions 3 of the rib, is formed a notch 4, as shown in Fig. 2. In connection with the jar shown in Figs. 1, 2 and 3 I use a cap 5 in the form of an inverted cup, having around its lower edge as many inwardly projecting fingers 6 as there are notches in the

rib, and to the under side of the cap is connected a disk 7 of resilient sheet metal, and, by preference, of a diameter substantially the same as that of the cover 2. In order to effect the closure of the jar said cover 2 is first applied to the top of the jar and the cap is held in such position that its inwardly projecting fingers 6 register with the thinner portions 3^a of the rib, and is then pushed downwardly until said fingers can, when the cap is rotated, pass beneath the thicker portions 3 of the rib, the elastic disk 7 being thereby caused to bear firmly upon the cover 2, and being subjected to such tension that, when the cap has been turned until its fingers are in register with the notches 4, release of pressure upon the cap will cause upward movement of the same which will carry the fingers 6 into said notches 4, whereby the cap is held against any further rotative movement and is securely locked against accidental displacement, removal of the cap necessitating first a downward pressure upon the same until its fingers are free from the notches and then a rotative movement until said fingers register with the portions 3^a of the rib, to which compound movement the cap is not likely to be accidentally subjected. The elastic disk 7 is preferably slotted, and its resiliency is such that, when the fingers of the cap are seated in the notches 4, sufficient pressure will be exerted upon the cover 2 to insure the desired close contact of said cover with the top of the jar.

In Figs. 4 and 7 I have illustrated the application of my invention to that class of jars in which an elastic packing ring 10 or disk 9 is seated upon an internal shoulder below the top of the jar, said ring or disk 9 being backed by a cover 2^a of glass or other relatively rigid material, through the medium of which the pressure of the spring member 7 of the closure is imparted.

In Fig. 5 I have illustrated another embodiment of my invention, in which the mouth portion of the jar is recessed for the reception of a cover 2^b, of glass or other available material, in order to prevent access of the contents of the jar to the packing ring 10, which is seated upon the top of the jar, and, in this embodiment of my invention I have also shown the cap 5^a as provided with a central depression 7^a, which constitutes the elastic member of the retainer, the cap being made of material possessing such resiliency as to render this por-

tion 7^a capable of exerting the desired yielding pressure upon the rigid cover 2^b.

While I prefer, in most cases, to construct the retaining member of the closure in the form of a cap, this is not absolutely essential to the proper carrying out of my invention, as a yoke carrying the spring member and having the desired number of arms for engagement with the notched rib of the jar 10 may be employed in place of such closed cap, if desired, such construction being illustrated at 11, in Fig. 6, or I may use a single bar yoke 12, as shown in Fig. 8, said yoke having fingers engaging with notches in a continuous rib on the jar, and being depressed in the center so as to form a spring member 7^b for bearing directly on the cover 2 of the jar, and this yoke may be mounted upon the cover, if desired, as for instance by riveting 20 it thereto, as shown at 13.

The thickened members 3 of the rib shown in Fig. 2 have abrupt ends, but they may, in some cases, be provided with inclined portions 14 leading to the notches, as shown, 25 for instance, by dotted lines in Fig. 7, the engagement of the fingers 6 of the retainer with these inclined portions serving to cause the depression of said retainer as the latter is turned after being applied to the jar.

30 A closure constructed in accordance with my invention can be cheaply made, it provides a neat and attractive finish for the top of the jar, and, when the retainer is in the form of a closed cap, it serves to protect the 35 cover, or cover and spring, from injury or displacement. Owing to the fact that the cover of the jar is held in place under a yielding pressure, any expansion of the contents of a full jar, either by heat or cold, which 40 is sufficient to exert a preponderating upward pressure on the cover, will cause said cover to lift and relieve the excessive internal pressure, thus preventing the breaking of the jar.

45 The notches in the under side of the thickened portions of the rib which surrounds the mouth of the jar extend to the outer face of said rib, and consequently do not interfere with the parting of the mold in which the 50 jar is formed. The notches for the reception of the fingers of the retainer may be formed in a member separate from the jar, as shown at 15 in Fig. 4, instead of in a rib integral

with the jar, said member either extending completely around the jar or only so far 55 around the same as to prevent its lateral removal, as preferred.

I claim:—

1. A jar having, around the mouth, a rib with notches in its underside which notches 60 have abrupt side walls, a cover for said jar, a retainer extending over said cover and having inwardly extending fingers for entering said notches, and also having an elastic member extending downwardly from the 65 retainer and having only a limited bearing upon the cover, said elastic member of the retainer exerting downward pressure upon said cover and upward pressure upon said fingers.

70 2. A jar having, around the mouth, a rib with notches in the underside of the same, which notches have abrupt side walls a cover for said jar, a retainer having fingers for entering said notches, and also having an 75 elastic member secured to the underside of said retainer, said elastic member exerting downward pressure upon said cover and upward pressure upon said fingers.

3. A jar having, around the mouth, a rib with notches in its underside, which notches have abrupt side walls a cover for said jar, a retainer having fingers for entering said notches, and an elastic member secured to the underside of said retainer, said elastic member bearing upon the cover immediately 85 above its seat upon the jar, and exerting downward pressure upon said cover and upward pressure upon said fingers.

4. A jar having, around the mouth, an 90 interrupted rib with notches in its underside, which notches have abrupt side walls, a cover for said jar, a cap having inwardly projecting fingers for entering the notches, and an elastic member secured to the underside 95 of said retainer and exerting downward pressure upon said cover and upward pressure upon said fingers.

In testimony whereof, I have signed my name to this specification, in the presence 100 of two subscribing witnesses.

LOUIS ESCHNER.
